UNITED STATES PATENT OFFICE.

ALEXANDER M. NICOLSON, OF NEW YORK, N. Y., ASSIGNOR TO WESTERN ELECTRIC COMPANY, INCORPORATED, OF NEW YORK, N. Y., A CORPORATION OF NEW YORK.

PIEZO-ELECTRIC LOUD SPEAKER.

Application filed December 31, 1923. Serial No. 683,643.

To all whom it may concern:

Be it known that I, ALEXANDER M. NICOLSON, a subject of the King of Great Britain, residing at New York, in the county of New York and State of New York, have invented certain new and useful Improvements in Piezo-Electric Loud Speakers, of which the following is a full, clear, concise, and exact description.

10 This invention relates to transforming one form of energy into another where one of the forms of energy is the energy of electric current waves and especially where the other form of energy is the energy of sound waves.

An object of the invention is an efficient and durable means for accomplishing such transformation, either of electrical energy to mechanical energy or vice versa, and especially an efficient and durable piezo-electric loud speaking telephone receiver capable of accurately reproducing voice current waves as sound waves of the same form.

In the form of the invention specifically shown and described herein for purposes of illustration, a piezo-electric crystal has extending through it and protruding from its walls an internal electrode, and the protruding parts of the electrode are used to securely and rigidly fasten the crystal in a band-shaped frame, and also to securely and rigidly fasten the crystal to an arm or plate which transmits elastic vibrations of the crystal to a diaphragm or the like.

35 Plates close the front and back of the frame, and means extending through one of the plates connects the tone arm and the diaphragm, which is preferably a fibrous conical diaphragm having a free periphery.

40 The material, form and mass of the frame are preferably such that it efficiently reflects the elastic vibrations of the crystal, so that the vibrations are efficiently transmitted to the diaphragm. Preferably, a

45 base supports the frame in such position that a horizontal plane through the apex of the diaphragm would pass between its axis and the lowest point on its periphery, so that the base need not be tall in order to bring

50 the lowest part of the diaphragm higher than the lowest part of the base. A tube containing water or Rochelle salt solution for moistening the interior of the crystal

may penetrate the crystal and be carried by it. Felt or the like may fill the space between the crystal and the frame and its front and back closure plates, to prevent production of undesired sounds.

In the drawing, Fig. 1 is a side elevation of a loud speaker embodying the invention; Fig. 2 is a front view of the device, with the diaphragm removed; and Fig. 3 is a front view of the device, with both the diaphragm and the base removed, and with the crystal and its frame in a vertical position.

The loud speaker comprises a base 5, a frame 6 mounted or supported on the base, a piezo-crystal 7 mounted in the frame, and a diaphragm 8 vibrated by the crystal. The crystal is preferably of the type disclosed in Fig. 8 or Fig. 12 of my article on the Piezo-electric effect in the composite Rochelle salt crystal, Proceedings of the American Institute of Electric Engineers, November 1919, page 1315, and is provided with a girdle-electrode 9 similar to the girdle-electrode shown in those figures; but the crystal 7 is provided with an internal electrode 10 instead of with the basal plane electrodes shown in said Fig. 12. The electrode 10 is shown by way of example as a bolt passing through the bottom of frame 6, through the crystal 7 in the direction of the principal axis of the crystal, through the top of the frame, and through a nut 11 at the top of the frame. Thus, the electrode 10 is in electrical connection with the frame which may be of electrically conducting material, for instance cast iron. The lower basal plane of the crystal is preferably cemented to the frame. The electrode 10 also passes through a torsion arm or plate 12, for example, of steel or the like, which is clamped against the top basal plane of the crystal by means of a nut 13 on the bolt 10. The plate 12 may also be cemented to the top basal plane of the crystal. A lead 15 is taken off from a point on frame 6 or from some other point in electrical connection with electrode 10; and a lead 16 is taken off from the girdle electrode 9. To insert the electrode 10 in the crystal, a hole may be drilled in the crystal, the electrode placed in the hole, and conducting material, such for example as tinfoil or graphite (not shown), tamped around the electrode to insure good

electrical connection between the crystal and the electrode; or the crystal may be grown about the electrode as described in my Patent No. 1,562,578, granted November 24, 1925.

5 The diaphragm 8 is preferably a conical diaphragm of fibrous material, for example, paper or the like, and has its apex rigidly attached to one end 18 of the torsion arm 12 so that vibratory elastic twisting of crystal 7 about its principal axis will vibrate the apex of the diaphragm in the direction of the axis of the diaphragm.

A tube of glass or the like, containing 15 water, Rochelle salt solution or the like for moistening the interior of the crystal may be carried by the crystal. Preferably one end of the tube is inserted in the crystal so as to penetrate to substantially the center of the 20 crystal and the other end of the tube is sealed. The part of the tube within the crystal may be cemented to the crystal. Preferably, a transparent closure plate 25 of celluloid or the like is attached to the front of 25 frame 6, for instance by means of screw 26, an opening 27 through plate 25 being provided for the passage of leads 15 and 16, and an opening 28 through the plate 25 being provided for the attachment of the apex of 30 the diaphragm to the torsion arm 12. The back of the frame is preferably closed by a plate similar to plate 25 which may, however, be of brass or the like.

The base 5 is shown as resting upon a 35 table top 35 or a like fixed support and as having one face 36 recessed as at 37 to receive the back of frame 6. The base may be, for instance, of wood or metal, and may, if desired, be rigidly fastened to the frame, 40 for example by screw bolts or the like (not shown) passed through the bottom portion 38 of the frame and into the base. Preferably the face 36 is inclined to the vertical in such a manner that, as shown in the drawing, a horizontal plane passed through the apex of the diaphragm would pass between its axis and the lowest point on its periphery, so that the base need not be tall in order to bring the lowest part of the diaphragm 45 higher than the lowest part of the base.

The principal axis of the crystal is preferably inclined to a vertical plane passed perpendicular to the face 36 of the base 5 and through the center of that face, so that 55 the frame 6 and the diaphragm 8 may each be symmetrically located with respect to that plane.

The bottom portion 38 of the frame 6, that is, the portion nearest the lower basal plane of the crystal, is preferably sufficiently massive to itself serve as a base for the crystal and insure that the frame will efficiently reflect elastic twisting vibrations of the crystal, so that the crystal vibrations will be efficiently transmitted to the diaphragm.

Of course, the frame 6 and base 5 may, if desired, be one integral casting. If the nut 11 is cramped or tightened against the frame 6 the crystal and its internal electrode will be more or less rigidly connected 70 to both the top and the bottom portions of the frame. This adjustment will increase the stiffness or elasticity of the structure comprising the crystal and the frame and, therefore, will increase the natural frequency of vibration of the structure. On the other hand, easing nut 11 off the frame will tend to increase the responsiveness of the loud speaker to low frequencies. 75

The loud speaker is reversible in its action, so it may also be regarded as a telephone transmitter.

The general principles herein disclosed may be embodied in many organizations 85 widely different from those illustrated, without departing from the spirit of the invention as defined in the appended claims.

What is claimed is:

1. In combination, a piezo-electric crystal, 90 a frame therefor, means for transmitting elastic vibrations of the crystal to a diaphragm, and internal electrode means for the crystal, said electrode means protruding through the surface of said crystal and engaging said first means and said frame. 95

2. In combinations, a piezo-electric crystal having side walls and end walls, a frame for said crystal, a member for transmitting elastic vibrations of the crystal to a diaphragm, and internal electrode means for the crystal, said means protruding from the end walls of the crystal and rigidly attached to said frame adjacent each end of said crystal, and rigidly attached to said arm. 100

3. In combination, a piezo-electric crystal, a band-shaped frame therefor, a member for transmitting elastic vibrations of the crystal to a diaphragm, internal electrode means for the crystal, said means protruding from the surface of the crystal and engaging said member and said frame, and means closing the front and back of said band-shaped frame to form a box-like enclosure for said crystal. 110

4. In combination, a piezo-electric crystal having side walls and end walls, a member at one end of said crystal for transmitting elastic vibrations of the crystal to a diaphragm, a frame for said crystal, said frame having a massive portion at the opposite end of said crystal for reacting against elastic vibrations of said crystal, and internal electrode means for the crystal, said means protruding from the end walls of the crystal and engaging said member and said frame. 115 120

5. In combination, a piezo-electric crystal, a band-shaped frame therefor, a fibrous conical diaphragm having a free periphery, a member for transmitting elastic vibrations 125 130

of said crystal to said diaphragm, internal electrode means for said crystal, said means extending through the surface of the crystal and engaging said member and said frame, means closing the front and the back of said frame, and means extending through said closure means and connecting said diaphragm and said member.

6. In combination, a piezo-electric crystal and a tube containing liquid for supplying moisture to the crystal, said tube being carried by the crystal and lying at least partly within it.

7. In combination, a piezo-electric crystal, a band-shaped frame therefor, a member for transmitting elastic vibrations of the crystal to a diaphragm, means extending from the surface of the crystal and engaging said member and said frame, means closing the front and back of said band-shaped frame to form a box-like enclosure for said crystal, and fibrous material between said crystal and said enclosure.

8. In combination, a piezo-electric crystal, a frame therefor, means for transmitting elastic vibrations of the crystal to a diaphragm, and means protruding through

the surface of the crystal and engaging said first means and said frame.

9. In combination, a piezo-electric crystal, means for transmitting elastic vibrations of the crystal to a diaphragm, a base for the crystal, for reflecting its elastic vibrations, and internal electrode means for the crystal, said electrode means protruding through the surface of said crystal and being rigidly connected to said base.

10. In combination, a piezo-electric crystal, a base therefor, and means for supporting said crystal from said base, and means comprising means penetrating said crystal and engaging said base.

11. In combination, a piezo-electric body, a base therefor having opposed portions, a rod-like member passing through said body and being attached to said opposed portions, means on said member for clamping said crystal to one of said portions and means adjacent said other portion for tensioning said member.

In witness whereof, I hereunto subscribe my name this 26 day of December A. D., 1923.

ALEXANDER M. NICOLSON.
